UNITED STATES PATENT OFFICE.

CHARLES Z. STEPHENS, OF RICHMOND, VIRGINIA, ASSIGNOR, BY MESNE ASSIGNMENTS, TO AMERICAN AUTOMATIC TRAIN CONTROL CORPORATION, A CORPORATION OF MARYLAND.

SYSTEM FOR AUTOMATICALLY CONTROLLING THE MOVEMENT OF TRAINS.

1,391,519.

Specification of Letters Patent. Patented Sept. 20, 1921.

Application filed December 20, 1918. Serial No. 267,684.

To all whom it may concern:

Be it known that I, CHARLES Z. STEPHENS, a citizen of the United States, residing at Richmond, in the county of Henrico and State of Virginia, have invented certain new and useful Improvements in Systems for Automatically Controlling the Movement of Trains, of which the following is a specification.

10. This invention relates to an improved system for automatically controlling the movement of trains.

In all train controlling systems, within my knowledge, in which the track rails are formed into insulated sections and ramp rails or other means are employed to transmit electrical energy to the vehicle to effect, on the latter, an indication of the condition of the track ahead, there exists a possibility 15 of the ramp rail or other means of the section through which the train is traveling, remaining energized, after the vehicle or train has passed such ramp or other means and before the vehicle has left the section 20 guarded by the passed ramp or other means, when for purposes of safety, such ramp or other means should become deenergized. Because of this possible condition in the operation of train control systems, a vehicle 25 might pass an energized ramp rail or other means, and then break down or, for some other reason be brought to a stop before it leaves the insulated section guarded by the ramp rail last passed, and if that last-passed 30 ramp or other means, remains energized, a train or vehicle following, would be given a false clear indication to proceed through the section, when as a matter of fact the preceding train or vehicle is still in the same 35 section.

The object therefore of this invention is to provide a system which will avoid these serious defects and which will effect a condition at the ramp rail or other means so 40 promptly as to prevent the approach of a second train or vehicle.

With this main and other objects in view, the invention is illustrated in the accompanying drawing, wherein a system embodying the invention in a simple form is 45 shown diagrammatically.

Referring to the drawing by numerals, 1, designates the track rails on which the vehicle or train travels, said rails being provided at intervals with insulating means 2, whereby to form blocks or sections. The blocks or sections thus formed by insulating the track-rails under the present invention are of two kind. One kind or set of these blocks is designated as 3, 5, 7, 9 and 11 while the other kind or set of blocks is designated as 4, 6, 8 and 10. One important difference between these two sets of blocks is that those comprising the set designated as 4, 6, 8 and 10 are very short as compared with those included in the set 3—5—7—9 and 11. These two sets of blocks are so arranged that a short block is located or interposed between two longer blocks.

In practising the invention I provide the shorter blocks with some form of means by which to transmit to mechanism on a vehicle, electrical energy to effect certain operations for the safe control of the train or vehicle.

The particular form of this energy-transmitting means may be varied and such current may be transmitted by induction or by current picked up from ramp rails.

In the present illustration of the invention I show ramp rails 12 and 13 at each short block section, and while these rails may have a staggered relation with respect to each other, I prefer to arrange them directly opposite for the reason that the short blocks which contain these ramps may be made sufficiently short, for reasons presently to be explained.

Inasmuch as under the present invention the short blocks or sections alone are provided with ramp rails or other energy-transmitting means I will hereinafter refer to them as the short ramp sections to distinguish them from the longer sections which have no ramps.

A track relay instrument, 14, commonly used in train control and signaling, is installed so as to connect the two rails at one end of each short ramp section and at the other end of each short ramp section I provide a battery or current-supply 15, whose poles are connected respectively to the two

track rails. By this means the track relay 14, of a section is kept energized so long as the short ramp section is clear, but will become deenergized upon the entrance of

5 a vehicle or train in that section.

The longer blocks or sections 3, 5, 7, 9 and 11 respectively each have their two rails at one end connected to the opposite sides of track relay instruments 16, and at the 10 other ends of said longer sections, the two track rails are connected to opposite sides or poles of a battery or current supply 17, so that as long as a longer block or section is clear, the track relay instrument for that 15 block will be kept energized and certain armatures of those relays will be held up to maintain certain circuits, as will presently be more clearly explained.

Each track relay 14, of a short ramp section has associated with it a line relay 18, while each track relay 16, of a long block or section has associated with it a line relay 19.

A ramp-rail battery or other current supply 20, is provided in connection with each 25 line relay 18, and normally this current supply has one pole or side connected to the ramp or other energy transmitting means of the short block with which said line relay 18, is associated.

30 The line relays 18 and 19 are energized by line batteries or current supplies 21, and while both of these relays operate to establish connections, under certain conditions between the ramp-rail current supply 20 and 35 the ramps, they are mainly utilized so that one will control the traffic in one direction while the other will control traffic in the reverse direction.

In practice it is desirable to locate the 40 track and line relays, one ramp-rail battery and a line battery, in one case or housing. Each line battery operates to supply current for a line relay of a block or section several blocks in the rear, and the maintenance of 45 the circuit depends upon the positions of the relay-armatures in the intervening blocks, said positions of the armatures being dependent upon the presence or absence of a train in such block or blocks.

50 Each track relay controls a plurality of armatures and each line relay also controls a plurality of armatures. The circuit between a line battery and the relay which that battery energizes, includes a plurality of intervening track-relay armatures, so that all those armatures must be held up to complete the circuit and energize the line relay in the rear of said line battery.

In accordance with the present invention 60 the line relays 18 and 19 are energized by stick circuits from their respective batteries and one line battery will control one line relay for traffic in one direction.

In order, in the drawing, to distinguish 65 the several track and line relays, the same

are lettered from A to P inclusive; the ramp batteries are lettered Q to T inclusive, and the line batteries are lettered U to X inclusive.

By reference to the drawing it will be 70 noted that the line relays I, K, M and O, operate to control traffic from left to right, while line relays J, L, N, and P, operate to control traffic from right to left.

Line battery U, normally, and during the 75 absence of a vehicle in block 4-5-6 and 7, energizes line relay M, while line battery V, normally energizes line relay O. To effect these energizations the current must pass through at least four armature-contacts 80 that are controlled by track relays. To make these connections clear, the circuit from line battery U, will be described after which the circuits from the other line batteries can be readily understood.

85 From battery U, the circuit would include wire 22; armature-contacts 23 and 24; wire 25; armature-contacts 26 and 27; wire 28 to contact 29; armature-contact 30 of line relay M; wires 31 and 32 to and through relay magnet M, thus forming a stick circuit, then return by wires 33, 34 and 35 to a common wire 36, and by branch wire 37, back to the negative side of line battery U. It will thus be seen that to 95 maintain the line relay M, from the line battery U, track relays A, B, C and D must all be energized in order to hold armature-contacts 23, 24, 26 and 27 in closed position. This means that blocks 4, 5, 6 and 7 must all 100 be clear.

If therefore a train enters the short ramp section or block 4, track relay A, will immediately become deenergized and all the armatures controlled by that relay A, will drop, 105 including armature-contact 23. When armature of relay A drops, contact 23 will drop and cause a break in the circuit from the line battery U, to line relay M, and this relay M, will also become deenergized and 110 drop its armature-contacts 30 and 38.

115 It will be noted that each line relay controls at least one contact, such as the contact 38, which is interposed between the ramp battery and the ramp rails 12-13, but that two such armature-contacts one of each of two line relays are provided between one ramp battery and its ramps. For example a train 39, is illustrated as occupying block or section 4, and another train 40, is in 120 block 11. Track relay A, is deenergized. Armature-contact 23, is down consequently relay M, is deenergized because current is cut off from line battery U to relay M. As relay M, is deenergized its contact 38, will be down.

In a similar manner train 40, in block 11, causes a deenergization of track relay H, and all of its contacts, including contact 41, will drop. When contact 41, drops current from 130

a line battery to the right of relay H, (not shown) will be cut off at the break between wire 42, and said contact 41, with the result that line relay M, will become deenergized. 5 When relay N, is deenergized contact 43, will drop.

Contacts 43 and 38, are both arranged in a ramp rail circuit from ramp battery S to ramp rails 12 and 13, of block 8, so that if 10 blocks 9, 10 and 11, were all clear relay N, would be energized and contact 43, would be up with the result that current from ramp battery S, could pass by wires 44, 45 to contact 43; then by wires 46 and 47, to the 15 ramps 12 and 13 of block 8, returning through the wheel of the vehicle to the track rails 1 and by wire 48, back to ramp battery S.

It will therefore be seen that current from 20 a ramp battery to the ramps supplied by that battery may travel through either of two armature-contacts each of which is controlled by a separate relay, and that before a complete break is effected between a ramp 25 battery and its ramps, both of these separately-maintained contacts must be dropped.

As a train 39, is presumed to be in short ramp section 4, and another train 40, is presumed to be in block or section 11, line relays 30 K, L, M and N will all be deenergized because of the dropping of the contacts of track relay A, and the dropping of the contacts of track relay H.

From the foregoing explanation it will be 35 understood that the circuit from a line battery to the line relay which it controls is checked through armature-contacts of a plurality of track relays; that a plurality of separately or independently operated contacts are arranged in the ramp-rail circuits and that both of said separately operated contacts must be dropped to effect a complete deenergization of the ramp rail, and that 40 each of the ramp-rail control contacts is in 45 turn controlled by a relay which is maintained by a stick circuit.

In practice, the short ramp blocks or sections 4, 6, 8 and 10 are preferably very short, say 300 to 350 feet long although this length 50 may be varied, whereas the long rampless sections or sections without ramps, are of sufficient length to permit a train running at high speed to be brought to stop within said long section.

55 In practice I have found that best results can be obtained if the short ramp sections are made of such length that the distance between each end of the ramp rails and the insulated joints at the same end of the section be slightly more than the distance between the contact shoes on two coupled-together engines so that the shoe of the second engine will leave the ramp rail before the 60 wheels of the first engine reach the insulated joints at the forward end of the short sec-

tion. If the distance between the end of the ramp and the insulated joint were less than the distance between two contact shoes on coupled engines, the first engine when crossing the joint would cause the breaking down 70 or dropping of the second of the two ramp-current control armatures and thereby deenergize the ramp before the shoe of the second engine clears that ramp and such deenergization of the ramp while the second 75 shoe is in contact therewith would cause a deenergization of the control magnet on the second vehicle and thereby produce a false stop.

Having described my invention what I 80 claim is,—

1. In a train control system the combination with the track rails provided at intervals with insulated joints and forming long and short insulated blocks, of a track relay 85 for each block, means along the shorter blocks only for transmitting electrical energy to a control mechanism on a vehicle and means for supplying electrical energy to the transmitting means along the said 90 shorter blocks said supplying means including two movable devices one of which is controlled by the approach of traffic in one direction and the other controlled by traffic in an opposite direction. 95

2. In a train control system the combination with the track rails provided at intervals with insulated joints and forming alternate long and short insulated blocks, of means along the short blocks only for transmitting electrical energy to a control mechanism on a vehicle, a current supply for each of the said transmitting means, two relays each having an armature, and a circuit between the current supply and the energy transmitting means, said circuit being maintained by either armature of said two relays. 100 105

3. In a train control system the combination with the track rails provided at intervals with insulated joints and forming alternate long and short insulated blocks, of a track relay for each block; means along the short blocks only for transmitting electrical energy to a control mechanism on a vehicle; a current supply for the said transmitting means; two independently-operable relays,—one controlled by traffic in one direction and the other controlled by traffic in a reverse direction and each relay having an 110 armature, connections from one side of the said transmitting current supply to both of said relay-armatures; connections from either of the two relay-armatures to the transmitting means along the shorter block 115 and connections from one of the track rails to the other side of the transmitting current supply. 120 125

4. In a train control system the combination with the track rails provided at inter- 130

vals with insulated joints and forming alternate long and short insulated blocks, of means along the short blocks for transmitting electrical energy to a control mechanism on a vehicle, a current supply for the transmitting means, two independent relays each energized by a stick circuit and each of

said relays having an armature, and connections between the transmitting current supply, the transmitting means and the track rail, said connections including an armature of each of said independent relays.

In testimony whereof I affix my signature.

CHARLES Z. STEPHENS.
